A coil spring unit 1 is conventional consisting essentially of a plurality of coil springs 2 connected to one another and to intervening supporting wires 3 and bordering wires 4 which in turn are preferably as shown, provided with an upper and lower fabric coverings 5 and 6 and padded units 7 between the upper and lower coverings 5 and 6 as shown in Fig. 1.

The novel feature of the present invention resides mainly in the padded units 8 and 9 now to be described. These padded units 8 and 9 according to the present invention are composed of a plurality of padded layers. In the present instance, each of the units 8 and 9 is illustrated as

composed of four layers such as the layers 10, 11, 12 and 13. In the preparation of these layers, a section of felt is passed through a carding machine with a sheet of muslin 14 and 15 above and below the same and the carding machine then

forms a plurality of parallel stitches 16 through

the three elements to secure the two muslin sheets 14 and 15 to the intervening layer of felt 17. In Fig. 1 preferably the outer layer 10, in place of the muslin sheet 14, has an outer sheet of ticking 18 attached thereto by the carding machine as shown. When a layer of felt passes through a carding machine according to the practice heretofore followed the fibres extend more or less longitudinally in the general direction of the path of movement and therefore with the row 10

of stitches. In the preparation of the first layer 10 according to the present invention, however, the felt 17 is passed through the carding machine with the fibres extending in the general direction transverse to the path of movement so that the stitches will be formed transverse to the general direction of the fibres. Furthermore according to the embodiment in Fig. 1, the stitches 16 of the first layer 10 will extend transverse to the length of the mattress. In preparing the second layer 11, the felt layer is similarly passed through the carding machine with the general direction of its fibres transverse to the direction of movement so that the stitches of the second layer, when attaching the muslin sheets to opposite sides thereof, still extend transverse to the general direction of the fibres. However, the fibres of the second layer 11 will extend in a general direction transverse to the length of the mattress and the stitches extend longitudinally of the mattress. The third layer 12 will have the general direction of the fibres again extend longitudinally and the stitches transversely of the mattress, similar to the arrangement of the layer 10, and the layer 13 will have its stitches and

felt fibres again arranged similar to that of the second layer 11. After each padded unit 8 and 9 is prepared as aforesaid, the outer layer 19 of the unit 9 similarly having the mattress ticking 20 secured to it as the ticking 18 is secured to the layer 10, then the beaded ends 21 and 22 of the outer layers 10 and 19 are connected to one another by the ends of an intervening fabric covering 23 as shown in Fig. 1.

It has been found that satisfactory padding units according to the present invention will also result when the felt layers are each attached to a single sheet of muslin as shown in Fig. 3, in which case, however, again the upper outer layer 24 will have the muslin sheet 25 and the mattress ticking 34 stitched thereto by the rows of stitches 26 transverse to the direction of the fibres, and also transverse to the length of the mattress, the next layer 27 will have its sheet of muslin 28 stitched thereto by rows of stitches 26 extending 55

MATTRESS

Joseph Martin, Laurelton, N. Y., assignor to United States Cabinet Bed Co., Brooklyn, N. Y., a corporation of New York

Application May 25, 1939, Serial No. 275,575

5 Claims. (Cl. 5—351)

This invention relates to mattresses in general and more especially to spring mattresses having two paddings composed of felt with an intervening section of coil springs. Among the objects of the present invention, it is aimed to provide an improved spring mattress having a pad composed of a plurality of sections one placed upon the other. It is still another object of the invention to provide an improved spring mattress having a padding composed of a plurality of layers, felt or the like, one placed upon the other and in which the general direction of the fibres of the alternate layers and the fibres of successive layers extend transversely to one another. It is still further another object of the present invention to provide an improved spring mattress having a padding composed of a plurality of layers of felt or the like, each attached to a muslin covering in which the stitches attach the muslin to the felt layer and successive layers extend transversely to one another. These, and other features, capabilities and advantages of the invention will appear from the subjoined detail description of specific embodiments thereof illustrated in the accompanying drawing in which—

Figure 1 is a fragmental section of a spring mattress made according to the present invention.

Fig. 2 is a fragmental plan of the mattress with portions broken away.

Fig. 3 is a fragmental section of another embodiment of the present invention.

In the embodiment shown in Figs. 1 and 2 the coil spring unit 1 is conventional consisting essentially of a plurality of coil springs 2 connected to one another and to intervening supporting wires 3 and bordering wires 4 which in turn are preferably as shown, provided with an upper and lower fabric coverings 5 and 6 and padded units 7 between the upper and lower coverings 5 and 6 as shown in Fig. 1.

The novel feature of the present invention resides mainly in the padded units 8 and 9 now to be described. These padded units 8 and 9 according to the present invention are composed of a plurality of padded layers. In the present instance, each of the units 8 and 9 is illustrated as composed of four layers such as the layers 10, 11, 12 and 13. In the preparation of these layers, a section of felt is passed through a carding machine with a sheet of muslin 14 and 15 above and below the same and the carding machine then

forms a plurality of parallel stitches 16 through the three elements to secure the two muslin sheets 14 and 15 to the intervening layer of felt 17. In Fig. 1 preferably the outer layer 10, in place of the muslin sheet 14, has an outer sheet of ticking 18 attached thereto by the carding machine as shown. When a layer of felt passes through a carding machine according to the practice heretofore followed the fibres extend more or less longitudinally in the general direction of the path of movement and therefore with the row 10 of stitches. In the preparation of the first layer 10 according to the present invention, however, the felt 17 is passed through the carding machine with the fibres extending in the general direction transverse to the path of movement so that the stitches will be formed transverse to the general direction of the fibres. Furthermore according to the embodiment in Fig. 1, the stitches 16 of the first layer 10 will extend transverse to the length of the mattress. In preparing the second layer 11, the felt layer is similarly passed through the carding machine with the general direction of its fibres transverse to the direction of movement so that the stitches of the second layer, when attaching the muslin sheets to opposite sides thereof, still extend transverse to the general direction of the fibres. However, the fibres of the second layer 11 will extend in a general direction transverse to the length of the mattress and the stitches extend longitudinally of the mattress. The third layer 12 will have the general direction of the fibres again extend longitudinally and the stitches transversely of the mattress, similar to the arrangement of the layer 10, and the layer 13 will have its stitches and

transverse to the general direction of the felt fibres but longitudinally of the mattress, the layer 29 and its muslin sheet 30 stitched similar to the arrangement of the layer 24 and the layer 31 5 and its muslin sheet 32 stitched similar to the arrangement of the layer 27.

With the practice heretofore followed, it has been found that when the mattresses extend in the general direction of the fibres naturally if 10 the fibres all extend in the same general direction there will result a compressed portion where the most weight supporting wear is exercised. With the present invention, with the fibres in successive layers extending in directions trans- 15 verse to one another and similarly the stitches of successive layers extending transversely to one another, the spreading out tendency of the successive layers will counteract one another sufficiently, materially to reduce the objection noted 20 with the mattress made according to the practice heretofore followed thereby materially increasing the fluffy life or good condition of the mattress.

It is obvious that the muslin sheets 14, 15 and 25 28 serve as protective sheets for their respective layers.

It is obvious that various changes and modifications may be made to the details of construction without departing from the general spirit 30 of the invention as set forth in the appended claims.

I claim:

1. A mattress including two padded units and an intervening coil spring unit, each padded unit including a plurality of felt fibre layers, a protective sheet for each layer, rows of stitches attaching each protective sheet to its layer, and extending transverse to the general direction of the fibres of its layer, the fibres of successive layers extending transverse to one another.
2. A padded unit for a coil spring unit consisting of a plurality of superimposed fibre layers, the general direction of the fibres of successive

layers extending transverse to one another, a protective sheet for each layer, rows of stitches attaching each protective sheet to its layer, and extending transverse to the general direction of the fibres, the rows of stitches of the successive 5 layers extending transverse to one another.

3. A padded unit for a coil spring mattress consisting of a plurality of superimposed fibrous layers, a protective sheet on each side of each fibrous layer, rows of stitches attaching the protective sheets of a layer to its layer and extending transverse to the general direction of the fibres thereof, the rows of stitches of successive layers extending transverse to one another. 10

4. A padded unit for a coil spring mattress 15 consisting of a plurality of felt fibre layers with the general direction of the fibres of successive layers extending transverse to one another, a muslin sheet for each layer, rows of stitches attaching each muslin sheet to its layer with the 20 stitches extending transverse to the general direction of the fibres thereof, the rows of stitches of successive layers extending transverse to one another.

5. A mattress including two padded layers and an intervening coil spring unit, each padded unit including a plurality of felt fibre layers with the general direction of the fibres of successive layers extending transverse to one another, a muslin sheet for each layer, rows of stitches attaching each muslin sheet to its layer and extending 25 transversely to the general direction of the felt fibres thereof, the rows of stitches of successive layers extending transverse to one another, a ticking sheet for the outer face of the outer layer 30 the rows of stitches of the outer layer attaching the ticking sheet to such layer, and ticking extending from the ticking of one outer layer to the 35 ticking of the other outer layer and connecting the two together. 40

JOSEPH MARTIN.
